UNITED STATES PATENT OFFICE.

THOMAS L. DENNIS, JR., OF STATEN ISLAND, NEW YORK.

SYNCHRONIZING MECHANISM.

Application filed November 17, 1917. Serial No. 202,530.

To all whom it may concern:

Be it known that I, THOMAS L. DENNIS, Jr., a citizen of the United States, residing at Staten Island, in the county of Richmond and State of New York, have invented certain new and useful Improvements in Synchronizing Mechanism, of which the following is a specification, reference being had to the accompanying drawings.

This invention relates to an improved synchronizing mechanism for moving picture film projecting machine and phonographs, display advertising, electric signs, stereopticon lectures, and for use in connection with analogous machines or apparatus where it is desired to operate the machines synchronously.

Broadly, also, the invention includes synchronizing one or more sound reproducing or musical instruments with the kinematograph, kinetoscope or other apparatus for producing animated or moving pictures; and it also broadly includes synchronizing a plurality of sound reproducing or musical instruments, stated broadly and without limitation to any particular such mechanism, irrespective of the moving picture apparatus.

It is the primary purpose of my invention to devise a relatively simple electromechanical mechanism which will automatically control the operation of a phonograph and a moving picture projecting apparatus whereby a monologue, dialogue, vocal or instrumental music, or sound of any other nature will be reproduced in absolute synchronism with the successive projection of the film pictures upon the screen.

It is one of the important objects of my invention to insure the instant discontinuance of the operation of the phonograph in accordance with the reproduction of the photo play, and the immediate resumption of the operation of the sound reproducing machine at maximum speed and at the proper times.

It is further one of the more particular objects of the invention to provide an improved brake and electrical means to release the brake.

It is also an object of my invention to provide a synchronizing mechanism the operation of which is primarily controlled through the medium of a perforated tape

or web. The tape or web is, as shown, preferably driven by a sprocket wheel and chain gearing. In case the synchronizing means be driven from a moving picture projecting apparatus, so as to synchronize the moving pictures with the sound reproducing or musical instruments, provision should be made for the case of breaking or tearing out of pictures from the film. This is in order to maintain the synchronism between the moving pictures and the accompanying talking or musical apparatus.

In the case of breakage in the film, or the tearing out of a section thereof containing a number of consecutive pictures, it is a well known practice for the moving picture operator to bring the broken ends of the film together, thus shortening the film by the number of pictures torn out. To meet this situation and maintain the synchronism between the moving pictures and the vocal accompaniment, I propose to tear out an equal or corresponding section from the tape in the synchronizer.

My improved synchronizing mechanism is also readily adaptable to use in conjunction with a multiplicity of sound reproducing machines, which may operate concurrently, or which may be successively and independently operated when the photo play is of such length that all of the spoken words or other sounds to be reproduced during the action of the play cannot be contained on a single record.

Further it is one of the detail objects of the invention to provide improved means whereby the perforated tape or web may be easily and quickly adjusted without operating the synchronizing mechanism.

It is also the general object and purpose of the present invention to provide a synchronizing mechanism as above characterized which is reliable in its operation, relatively simple in construction and not liable to get out of order and which may be used in connection with moving picture projecting machines now known in the art, without necessitating any alterations whatever in the construction thereof.

With the above and other objects in view the invention consists in the combination, construction and relative arrangement of the several parts hereinafter more fully described in detail, subsequently claimed and illustrated in the accompanying drawings.

in which similar reference characters designate corresponding parts throughout the several views; and wherein—

Figure 1 is a side elevation illustrating the mounting and arrangement of the tape or web reel and spool the operating means for the synchronizing mechanism and the driving connection between said operating means and one of the constantly driven shafts of the picture projecting apparatus.

Figure 2 is an elevation looking at right angles to Figure 1, the electrical connections between the several circuit closing devices on the operating shaft and the sound reproducing machines being diagrammatically illustrated;

Figure 3 is an enlarged side elevation of one of the sound reproducing machines and the brake controlling means therefor;

Figure 4 is a top plan view of the sound reproducing machine, a portion of the record disk being broken away;

Figure 5 is an enlarged vertical section taken on the line 5—5 of Figure 4;

Figure 6 is a horizontal section taken on the line 6—6 of Figure 5;

Figure 7 is an enlarged detail section taken on the line 7—7 of Figure 3;

Figure 8 is a section taken on the line 8—8 of Figure 1;

Figure 9 is a section taken on the line 9—9 of Figure 8;

Figure 10 is a section taken on the line 10—10 of Figure 1;

Figure 11 is a detail elevation illustrating a slightly modified means for closing the circuit of the escapement mechanism through the perforated tape.

Figure 12 is a diagrammatic view illustrating the circuits for the escapement mechanisms of the sound reproducing machines;

Figure 13 is a similar view showing the circuit for the brake devices of the several sound recording machines;

Figure 14 is a detail elevation of certain of the parts of the mechanism; and

Figure 15 is a detail view of certain other parts of the mechanism.

Figure 16 is an end view of the parts shown in Figure 15.

Referring in detail to the drawings 5 designates the spaced uprights of a supporting frame which are rigidly connected at spaced points as indicated at 6. The frame uprights at their upper ends are formed with suitable bearings seats 7 to receive the ends of the reel shaft or spindle 8. 9 designates the upper reel and 10 the lower reel, the latter being mounted between the frame uprights 5 in a manner which will be herein-after more particularly described. These reels may be of the usual sheet metal skeletonized construction such as are generally employed in a moving picture projecting ap-

paratus. Upon one end of the shaft 11 of the lower reel 10 a sprocket 12 is fixed. The frame uprights 5 at one side of the lower reel 10 are formed with laterally projecting portions in which a feed shaft 13 is mounted. On this shaft a sleeve 14 is loosely engaged and is provided upon one end with a peripherally toothed feed wheel 15, preferably integral with said sleeve. A similar wheel 16 is engaged on the other end of said sleeve 14 and between these feed wheels 15 and 16 a cylindrical bushing 17 of insulating material surrounds the metal sleeve 14. This bushing is peripherally grooved to receive the metal current conducting band or sleeve 18. The feed wheel 16 is retained in place on the sleeve 14 by means of a collar or nut 19 threaded on the end of said sleeve.

To one end of the shaft 13, a flanged collar 20 is secured by means of the screw or bolt 21 which is axially threaded in the end of said shaft. The collar 20 is also preferably provided with ribs or keys indicated at 20' to engage in grooves in the face of the shaft 13. A sleeve 22 is loosely engaged upon the latter end of the shaft 13 and is provided upon one end at diametrically opposite points with longitudinally projecting key lugs 23 which are movable through correspondingly located openings 24 in the flange of the collar 20. A pinion 25 is fixed on the other end of the sleeve 22 and is provided upon one face with an annular series of teeth 26 with which diametrically opposed teeth 26' on one face of the feed wheel 15 are adapted to engage. A flange 27 is spaced from the opposite face of the pinion 25 and is integral with said pinion to provide an annular groove which receives the forked or bifurcated end of the leaf spring 28, the other end of which is suitably secured to the inner face of one of the frame uprights 5. This spring normally acts to yieldingly hold the teeth 26 on the pinion 25 in engagement with the teeth 26' upon the feed wheel 15, thus locking the feed wheels 15 and 16 to the shaft 13 through the medium of the key lugs 23 and the collar 20 so that all parts will have a unitary rotation. A pin 29 is movable through the frame uprights 5 and is connected at its inner end to the leaf spring 28 adjacent the free end thereof. By pulling this pin outwardly, the spring is flexed and the sleeve 22 and pinion 25 is forced outwardly on the end of the shaft 13 so as to disengage the teeth 26 on said pinion from the teeth 26' on the feed wheel 15. The reason and purpose of this particular mounting and operating means for the circuit closing sleeve 18 will herein-after become apparent. On the other end of the shaft 13 a relatively large sprocket wheel 30 is fixed. 31 designates the drive chain which traverses this sprocket wheel 30. One stretch of this chain passes over the sprocket 30

wheel 12 on the lower reel shaft 11. This chain is engaged around a sprocket wheel 32 fixed upon one of the constant speed shafts of the picture projecting machine indicated at 33. As above indicated, however, the sprocket wheel 32 may be driven by means other than the picture projecting machine, as say where sound reproducing or musical instruments are to be synchronized with each other for combined and independent musical effect without the accompaniment of the moving pictures.

A second shaft 34 is journaled in the laterally projecting portions of the frame uprights 5 and disposed in parallel relation to the shaft 13. On one end of this shaft 34 a pinion 35 is keyed or otherwise suitably fixed and has meshing engagement with the pinion 25 on the shaft 13. Upon the central portion of the shaft 34 and suitably insulated from said shaft and from each other the rings 36 are arranged, said rings being of copper or other metal of high electrical conductivity. Each of these rings is formed with an annular groove 37 opening upon one side face of the ring. The body of the ring is further provided with a plurality of spaced radially extending openings 38 communicating with said groove. In each of these openings, a pin 39 is loosely engaged, and said pin is provided intermediate of its ends with a notch 40 in its periphery to receive one edge of a resilient sheet metal annulus 41 which is engaged in the groove 37 and normally in contact with the outer peripheral wall of said groove. This resilient band or annulus acts to urge the series of pins 39 outwardly and project their outer ends slightly beyond the peripheral face of the ring 36.

42 designates a tape or web of paper or other insulating material. An obsolete moving picture film may also be utilized. This tape 42 is wound upon the reel 9, and the end of the tape connected to the lower reel 10, said tape passing around the conducting sleeve 18 and between the same and the series of rings 36, as clearly shown in Figure 1 of the drawings. A resilient contact 43 has frictional bearing engagement at its free end upon the periphery of the sleeve 18, the other end of said contact being engaged with the terminal of a wire 44, which furnishes a current from a suitable supply source. This wire terminal and the spring contact 43 are fixed to a bar of insulating material indicated at 45 secured to the reel frame. To a second insulating bar 46 mounted in the reel frame, a series of resilient metal brushes 47 are fixed at one of their ends, said brushes corresponding in number to the number of rings 36 and having longitudinal slots 48 in their other ends to accommodate the projecting ends of the pins 39 in the re-

spective rings. The latter ends of the brushes are slightly curved and have resilient frictional engagement upon the peripheral faces of the rings 36. A current conducting wire 49 is connected to each brush 47 through the medium of which the brake control magnets of a series of sound reproducing machines indicated at 50 are energized. The particular construction and manner of operation of the brake control mechanism will be subsequently related.

The tape or web 42 is provided adjacent each of its side edges with spaced perforations 51 in which the cogs or teeth of the feed wheels 15 and 16 are adapted to engage. The tape 42 is also provided with additional longitudinally extending spaced rows of perforations 52, preferably of rectangular shape and through these latter rows of perforations, the ends of the pins 39 carried by the respective rings 36 are adapted to engage and contact with the current conducting sleeve 18. Each of the latter perforations in the tape corresponds to one picture upon the film of the projecting apparatus where such apparatus is employed, where four of the feed openings or perforations in the film correspond to one of the pictures. A one thousand foot moving picture film therefore requires 250 feet of the tape or obsolete film which controls the synchronizing mechanism of the phonograph. If the film of the picture apparatus should break so that it is necessary to remove a number of pictures, a section of the tape 42 having the same number of holes or perforations 52 therein is removed at a point nearest to where the break occurs and behind it at a point where the phonograph is not operated. Or if desired, in lieu of this method, and in order to maintain absolute synchronism in the operation of the projecting apparatus and the phonograph, a section of plain film equivalent in length to the mutilated portion of the moving picture film which is removed may be substituted. In producing the phonographic records, advantage should be taken of those situations in the action of the play where no sound or spoken words is required from the record to stop and start, so that provision can be made for breaks in the film. Considerable space on the record disk may also be saved.

Each of the phonographs 50 includes a table 53 having a hub 54 which is provided with a gear 55. Between the hub 54 and a standard 56 rising from a suitable base, antifriction bearings 57 are arranged. The table 53 which is of relatively small diameter supports the record disk indicated at R. This disk is provided with a plurality of openings in spaced concentric relation to its axis which receive the ends of pins or studs 58 fixed in the table 53 whereby the record disk is held against shifting move-

ment with respect to the supporting table. The disk R is further provided with a central opening to receive a rod or bolt 59 which also extends through an axial opening in 5 the table 53 and has threaded engagement in a bore formed in the standard 56. This rod or bolt is provided with a knurled head 60 for clamping engagement upon the center of the disk R.

10 61 designates the driving gear for the record disk table which has constant meshing engagement with the gear 55, said driving gear being operated by a spring or any other preferred motive power. The gears 55 and 15 61 are of such ratio as to rotate the record table at the proper speed. The ratio illustrated in the accompanying drawing will produce a maximum operating speed of 90 revolutions per minute. Of course, in order 20 to obtain absolute synchronism in the operation of the projecting apparatus and the phonograph, it is essential that the rotation of the record table shall be started at a maximum speed. In order to attain immediate 25 maximum speed when the circuit is closed, therefore, I employ, in addition to the usual spring motor for the phonograph, shown in Figure 4 and indicated by the reference character M, the two magnetically operated 30 clutch levers 100, 100, located on diametrically opposite sides of the record disc R. These two levers are pressed against the edges of the disc by the springs 106, 106, which latter are provided with tension regulating screws 107, 107 and their adjusting nuts. When the circuit is open the two levers 100, 100 act as brake levers, under the 35 impulse of their springs 106, 106. But when the circuit is closed they are drawn powerfully toward their solenoids 98, 98, and since 40 they are still pressed against the disc R by their springs 106, 106 they instantly drag the disc R forward at full speed until they are dragged by their solenoids up onto the beveled lugs 102, 102, away from the disc. But 45 in this short movement the disc has attained full maximum speed by the powerful pull of the solenoids 98, 98 and their clutch levers 100, 100, in addition to the pull of the 50 usual motor M (see Fig. 4). As soon as the clutch levers 100, 100 are dragged up onto the beveled lugs 102, 102, free of the periphery of the disc R, the disc is freed therefrom and being already at full maximum speed, 55 will so continue. When, however, the current is again cut off and the solenoids de-energized, the springs 106, 106 will again pull the levers 100, 100 down off from the lugs 102, 102 onto the edge of the disc R, whereupon 60 they will act as brake levers to bring the record disc from full maximum speed to instant stark stand still. Hence the levers 100, 100 alternately perform the function of driving clutch levers and stopping 65 and holding brake levers. They are brought

into action as driving clutch levers by the solenoids 98, 98 which are energized by the first escapement impulse. Hence it is obvious that the only thing required to bring the record disc from stark stand still to instant maximum speed is that the springs 106, 106 be sufficiently tensioned to prevent any slipping of the clutch levers 100, 100 on the edge of the disc R and that the solenoids be sufficiently energized to drag the clutch levers 100, 100 and thus the record disc R up to instant maximum speed in the short space before the levers are dragged up onto the beveled lugs 102, 102 free of the disc. This is precisely what I do to start the disc at 70 maximum speed and then to again bring it to instant stark stand still. It will also be noted that when the disc is being again brought to instant stark stand still the levers are moving frictionally on the edge of the 75 disc under the pressure of the springs 106, 106, in a direction the reverse of the movement of the disc, thus serving to overcome the momentum of the disc and bring it instantly to the stark stand still position of 80 rest.

The means ordinarily employed for starting the disc record of a phonograph is the usual motor, here shown as M, and the disc record comes gradually up to full speed. 85 This is the method with the popular phonograph in common use. But here, where synchronism is required between a plurality of mechanisms, with one machine running full speed and another starting in, the latter 90 must of course start in also at full speed. Hence we must employ means in addition to the motor to give sufficient power to force the disc record to start at maximum speed; but such additional powerful means may be 95 discontinued immediately the record is brought up to full speed.

It is obvious that the method above described will meet these requirements, and we will now describe it in detail. But in order 100 to close the circuit and start the disc record, one impulse of the escapement is required, and we therefore also provide means for starting the escapement at maximum speed. Hence we will first describe in detail the latter 105 means and then the means in detail for starting the record disc at maximum speed, as above broadly indicated.

In the base or bed plate of the phonograph a vertically disposed rod or axis 62 is 110 rotatably mounted in spaced relation to the table supporting pedestal or standard 56, said axis extending through openings in the spaced arms 63 of a casting 64 which is suitably secured upon the bed plate. Between 115 the arms 63, a sleeve or collar 65 is suitably fixed upon the axis 62 and has an annular flange 66 formed on one of its ends. An annular insulating ring 67 of channel shaped form in cross section is engaged upon said 120

sleeve and tightly held against the flange 66 by means of a nut 68 threaded upon the opposite end of said sleeve. A pair of ratchets 69 are engaged upon the insulating ring 67, said ratchets being insulated from each other by a spacing annulus or washer 70 interposed between the same. The outer edge of each ratchet having the teeth formed thereon is of increased thickness to provide an annular shoulder indicated at 71 in the outer side of the ratchet. These shoulders on the respective ratchets are frictionally engaged by the resilient metal contact plates 72 which are fixed at one of their ends upon an insulating bar 73 secured to the upright 64. 74 designates a double pawl which is oscillatably mounted between the conical bearing screws 75 secured in the ends of the arms 63. The end portions of this pawl on opposite sides of the bearing screws are laterally offset, each of said end portions having a single tooth 76 disposed in the plane of the respective ratchet wheels 69 for engagement with the teeth thereof. Each end of the pawl 74 is formed with a terminal lug 77 which is opposed to the core of one of the electromagnets 78 mounted upon the base or bed plate of the phonograph. The pawl 74 is held against casual oscillation by the leaf springs 74' the tension of which may be adjusted by means of the screws 74a. It will be understood that a starting and stopping mechanism is provided for each of the individual phonographs which may be used in conjunction with the moving picture apparatus. One of the wires 49 is connected to the corresponding terminals of the magnets 78, while the other terminals of the magnets 78 are connected by means of wires 79 to the fixed ends of the respective spring contact plates 72.

To the upper end of the casting 64 a horizontally disposed arm 80 is fixed at one of its ends. A gear 81 which is in constant meshing engagement with the gear 61 is provided with a shaft or axis 82 one end of which is rotatably mounted in the other end of the arm 80, said gear being held in its assembled position upon the arm by means of a set screw 83 which has threaded engagement in the end of the gear axis extending through the arm. The other end of the gear axis 82 is formed with a bore 84 to receive the upper end of the escapement ratchet shaft 62. The gear 81 is further provided on one face with an enlarged hub 85 surrounding the axis 82, and upon said hub a flanged sleeve 86 of insulating material is engaged. A metal sleeve 87 is in turn fixed upon this insulating sleeve and projects beyond the gear hub 85, such projecting portion of the sleeve having an annular groove 88, in its outer peripheral face. The base wall of this groove is provided with an arcuate slot or opening 89. A

split resilient metal contact strip 90 is engaged in the groove 88 and is capable of a circumferential movement therein. One end of this split contact band is angularly offset as at 91 and extends through the opening 89 in the sleeve 87, the terminal of said offset end of the band extending in concentric spaced relation to the inner wall of the sleeve. 70

An annular collar 92 is disposed upon the shaft 62 between the upper casting arm 63 and the sleeve 87, the body wall of said annular collar being disposed in spaced concentric relation to the shaft 62. One end of this collar is reduced in diameter as at 93 and keyed or otherwise fixed to the shaft 62. A section of the annular body wall of the collar 92 is cut out as at 94 and to one of this body wall, a block of insulating material 95 is securely fixed. 80 When the parts are assembled, the body wall of the collar 92 is disposed within the reduced end of the metal sleeve 87 and in the radial plane of the circuit closing contact strip 90. A coiled torsional spring 96 is engaged upon the upper end of the shaft 62 within the annular collar 92 and has one of its ends fixed to the reduced end 93 of said collar and its other end fixed to the hub 85 of the gear 81. A third circuit closing contact spring 97 is fixed at one end to the insulating bar 73 and at its other or free end has frictional bearing engagement upon the body portion of the sleeve 87. 85

Solenoids 98 are arranged at diametrically opposite sides of the record R and on relatively opposite sides of the axis of the table 53. The core rod 99 of each solenoid is connected to the upper end of a brake bar or lever 100 the lower end of which has a ball 101 and socket mounting 101 in the bed plate of the phonograph. In spaced relation to each of the brake levers 100, a fixed vertical post or standard 102 is mounted upon the bed plate. This standard at its upper end has a beveled or chamfered face 103 with which a beveled face 104 on the brake lever 100 is adapted to engage. Above this beveled face 104 the lever 100 is provided with a brake block 105 of suitable friction material which is adapted for engagement with the perimeter of the record disk. To each brake lever 100 one end of a coiled contractile spring 106 is attached adjacent the upper end of the lever, the other end of the spring being 110 connected to a tension adjusting or regulating screw 107 mounted in a standard 108 in the bed plate of the machine. It will be noted from reference to Figure 3 that the springs 106 are disposed at a downward inclination from the brake levers and extend inwardly beneath the record disk. Thus the springs normally tend to pull the upper ends of the brake levers circumferentially with respect to the disk and inwardly to engage 115 120 125 130

the friction blocks 105 with the edge of the disk. The corresponding terminals of the solenoids 98 are connected by the wire 109. The 5 other terminal of one solenoid is connected to a suitable source of electrical current, and the other terminal of the other solenoid is connected by the wire 110 to the circuit closing contact 97.

10 I have also devised means whereby the reels for the tape 42 can be easily and quickly removed and have also provided simple and effective means for axially adjusting the reels whereby the two reels may be properly 15 aligned to assure the free winding movement of the tape or web without binding in the operation of the machine. To this end, therefore, I provide for the upper reel 9 the semi-circular friction pads 111 fixed upon 20 the bifurcated ends of the spring plates 112 and 113 respectively. These plates at one of their ends are secured to the inner faces of the spaced uprights 5 of the reel frame and a pressure regulating screw 114 has 25 bearing engagement with the free end of the spring plate 113 whereby the desired frictional pressure of the pad 111 on said plate against the side of the reel 9 may be obtained. The other spring plate 112 is 30 provided with an angularly offset medial portion 115 and an adjusting screw 116 threaded in the frame upright 5 below the offset 115 in said spaced plate is provided to vary the pressure of the pad 111 against 35 the opposite side of the reel 9. This pad may be released from frictional contact with the reel to permit of the axial adjustment of the reel by the manipulation of the screw 114, and for this purpose I provide a rod 40 117 axially shiftable in the frame upright 5 and having a reduced end fixed to the bifurcated end of the plate 112.

The axis 11 of the lower reel 10 has a bore 118 formed in one end thereof. An 45 arm 119 is pivotally mounted at one of its ends as at 120 upon the frame upright 5 for lateral swinging movement. The other end of this arm is split as at 121, the split portions being connected by a clamping screw 122. This split end of the arm is 50 provided with a threaded opening to receive the threaded shank 124 of a flanged sleeve 123. Upon this sleeve an annulus 125 is loosely mounted to rotate. One end of a 55 spring 126 is fixed to the annulus and at its other end is engaged with the side of the reel 10. A rod or pin 126 extends through the sleeve 123 and said rod in one position is engaged in the bore 118 of the 60 reel axis 11. This rod is provided with spaced annular grooves 127 and 128 in its periphery, and in the operative position of said rod or pin the free end of a wire spring 129 is engaged in the groove 127 which is 65 nearest the end of said rod. Thus the rod

126 coating with the axis of the reel 10 supports the reel in the frame. The pressure of the spring 125 against the reel may be regulated and adjusted by turning the flanged sleeve 123 as will be readily understood. The pivoted end of the arm 119 is provided with an extension adapted to be connected to the member 136 pivoted as at 70 137 on the frame member 5, by means of the screw 137. This screw is adapted to be removed and the part 136 swung upon its pivot out of the path of movement of the end of the arm 119. In order to remove the reel 10, it is only necessary to pull the rod 126 outwardly to thereby disengage its end 75 from the bore 118 of the reel axis and until the spring 129 on the arm 119 engages in the inner annular groove 128 in said rod. The arm 119 may now be easily swung outwardly away from the reel so that the reel 80 can be removed through the skeletonized frame upright 5. It is of course understood that one end of the spring 125 will be fixed to the flanged sleeve 123 so as to obviate the possible loss of said spring. 85

The other end of the reel axis 11 is reduced in diameter as at 130 and is axially bored, the outer end of said bore being threaded to receive the threaded shank portion of a rod 131. A plate or disk 132 is 90 loosely engaged on the shaft 11 and is provided with a friction pad 133 for engagement with the reel 10. This plate is provided with bearing lugs to receive the ends of a pin 134 which is movable in a slot 135 95 formed in the body of the reel axis 11. With this pin 134, the inner end of the adjustable rod 131 is engaged. Thus it will be obvious that by the adjustment of this rod 131, the frictional pressure of the pad 100 133 against the reel 10 can be properly regulated as conditions may necessitate. By the adjustment of the rod 131, the wear upon the pad 133 may also be compensated for. 105

Having now described the construction and relative arrangement of the several parts, the operation of the synchronizing mechanism will be understood as follows:

Two or more sound reproducing machines 110 115 may be used in connection with the picture projecting apparatus, and while I have shown four such machines in the accompanying drawings, two reproducing machines will suffice for any length of film, as the record on one machine can be changed or replaced by a new record while the other machine is in operation, and the current again directed for the control of the first machine when the second is exhausted. 120 However, when it is necessary to reproduce a multiplicity of different sounds so that they will be readily distinguishable, even a larger number of phonograph machines 125 than as herein illustrated may be provided, 130

it being only necessary to increase the width of the tape or web 42 and the number of rows of perforations 52 in said tape with a corresponding increase in the number of the conductors 36.

As above stated, it is essential in the operation of the escapement mechanism of the phonograph in order that the perfect synchronization of the two machines shall be obtained, that the escapement wheels or ratchets shall stop and start at maximum operating speed. To insure this result, I provide the flexible or yieldable connection between the escapement mechanism and the electrical control means for the record disk brakes above referred to so that the record disc will be in advance of the escapement mechanism, or in other words when the phonograph is not in operation, there will be a tension upon the operating gearing for the phonograph disk table, which tension is augmented by the action of the electromagnets 78 which insures the instant operation of the escapement mechanism at maximum speed when the circuit is alternately closed through the magnets. Assuming that the brakes are applied to the edge of the record disk, when a point is reached in the projection of the film pictures which is to be accompanied by spoken words or sounds from one of the reproducing machines, one of the spring pressed pins in one of the conductors 36 corresponding to the reproducing machine is projected by the resilient band 41 through one of the apertures or perforations 52 in one row in the tape 42 so that the pin will contact with the current conducting sleeve 18. A circuit will therefore be closed through the wire 44, spring contact 43, sleeve 18, pin 39, ring 36, contact 47, wire 49, magnet 78, wire 79, and spring contact 72 to the ratchet 69 and through the pawl in contact with said ratchet to the ground.

As stated above, the teeth 76 at the opposite ends of the double pawl 74 are laterally offset so that one tooth engages the upper ratchet or escapement wheel 69 and the other tooth the lower ratchet or escapement wheel 69 (see Fig. 5). Referring to Fig. 4 it will be seen that the wire 79 which is connected to the inner magnet 78, extends to the lower contact plate or brush 72, which latter at its free end engages the annular shoulder 71 of the lower ratchet wheel 69 (see Figs. 3 and 7). In Fig. 4 the tooth 76 of pawl 74, which is offset in the plane of the lower ratchet wheel 69, is shown engaged therewith and the tooth offset in the plane of the upper ratchet wheel is disengaged. Hence with the parts in the position shown in Fig. 4 and in the initial operation above described the current will flow through the inner magnet (Fig. 4) to the wire 79 which connects with the lower spring contact 72 (Fig. 3) and through that spring contact to the lower

ratchet wheel 69. The inner magnet 78 being thus energized, its core will immediately act on the terminal lug 77 (see Fig. 4) to disengage the tooth 76 from the lower ratchet wheel and to move the opposite tooth into position to engage a tooth of the upper ratchet wheel as soon as the ratchet wheels have been rotated into engagement therewith.

Thereupon when the next succeeding tooth engages through the next succeeding perforation 52 with the sleeve 18 the current will flow to brush 47 and wire 49 to the magnets 78, and the outer magnet will be energized and the upper tooth 76 disengaged from the upper ratchet wheel and the lower tooth re-engaged with the lower ratchet wheel; and so on as long as succeeding pins 39 engage through perforations 52 with the current conducting band 18. The magnets 78 will be alternately energized and the teeth 76 alternately withdrawn from the upper and lower ratchet wheels.

Referring again to the initial operation, immediately upon the operation of the escapement mechanism, the spring 96 which is normally under tension operates to rotate the escapement ratchets and shaft 62 at maximum speed. In the initial operation the collar 92 is rotated to engage its wall with the inwardly offset end of the band 90 which is mounted on the sleeve 87. Fig. 6 shows the position after said initial operation, the collar 92 having been rotated in the initial operation into contacting engagement with the inwardly offset end of the band 90. In this figure the parts are viewed from below whereas in the adjacent Fig. 7, showing the escapement ratchet wheels 69, the view is from above. Hence in Fig. 7 the movement of the wheels appears as a clockwise movement, whereas in Fig. 6 the associated escapement parts appear as moving in an anti-clockwise direction. In reality, of course, they all move in the same direction, being operatively connected together, the apparent difference of direction being due to the different point of view, the one from above and the other from below. By reference to Fig. 5, showing, in section, all of the parts shown in Figs. 6 and 7, it will be apparent how the parts viewed from above will appear to move in a clockwise direction, whereas viewed from below they will appear as moving in the opposite direction.

By the contacting engagement of the inwardly offset end of the band 90 with the collar 92, as shown in Fig. 6, the second electric circuit is closed, namely the circuit taking its current from a source of supply, as illustrated in Fig. 4 by the feed wire (unnumbered) extending above the left hand magnet 98 in the figure, thence through connecting wire 109 to the left hand magnet 98 (same figure) and thence through wire 110, 120

spring contact 97, sleeve 87, bar 90, collar 92 and shaft 62 to the ground. The core rods 99 of the solenoids 98 will be retracted and move the brake blocks 100 in a clockwise direction, thus first starting the record disc table R at maximum speed and then disengaging the brake shoes 105 on said blocks from the edge of the record disk. The inclined faces 104 on the brake blocks 100 contacting with the faces 103 of the standards 102, effects an outward lateral movement of the brake blocks 100 against the action of the springs 106 so that the brake shoes 105 will be prevented from being drawn into braking engagement with the edge of the disk by said springs. The disk being thus released after having been brought up to maximum speed, the motor operated gear 61 which drives the disk table continues to rotate the table at maximum speed so long as the electric impulses continue to be imparted from the synchronizer or synchronizing machine, through the circuits 49 to the phonographs 50, as is graphically illustrated in Figures 2 and 12, to operate the escapement ratchets 69, as is also graphically illustrated in Figure 12.

It is obvious from the above that after the disengagement of one tooth 76 from its ratchet wheel, the ratchet wheels must rotate far enough to engage the other tooth 76 with its ratchet wheel, because the teeth of the two ratchet wheels are staggered relatively to each other (see Fig. 7), and the current will only flow through the tooth 76 to the ground upon such engagement. Hence there must be a step by step movement of the escapement, as is common in all escapements.

But since the phonograph record table R is meantime rotating continuously, as is necessary in order to maintain its momentum and maximum speed and for correct musical effect and the spoken words, it will be obvious that some means must be provided to rotate the escapement or ratchet wheels at a relatively higher speed than that of the record table R, during the portions of the whole period of rotation of the table R in which the wheels 69 are rotating. This is necessary in order to preserve the synchronism. The means provided for this purpose consist of the coiled wire tension spring 96, interposed between the escapement mechanism and the gear 81, which latter rotates with the phonograph record table R. This spring provides flexibility between the escapement and the phonograph which permits of a continuous rotation of the phonograph at uniform speed, while the escapement is performing its step by step movement in synchronism therewith. This operation continues as long as one of the pins 39 is in engagement with the sleeve 18 through the perforated tape 42, the magnets 78 being alternately energized to operate the escapement pawl 74 as will be readily understood. Of course when there is a break

in the row of perforations 52, the pins mounted in the ring 36 will be forced inwardly against the action of the resilient band 41 as they successively contact with the imperforate portion of the tape, and the circuit is then broken so that the operation of the escapement mechanism instantly stops, and the offset terminal of the band 90 on the sleeve 87 is moved out of engagement with the collar 92, until the offset in the band contacts with the insulating block 95 on said collar. Thus the circuit for the solenoids 98 is also broken and the contractile springs 106 immediately act to engage the friction shoes 105 on the brake blocks 100 with the edge of the record disc, thus bringing the latter to an abrupt stop. In this relative rotation of the disk table with respect to the escapement mechanism, the spring 96 is again placed under maximum tension so that it will operate to actuate the escapement mechanism at maximum speed when the circuit is again closed, and thereby also engage the band 90 to close the circuit of the brake mechanism. Thus the record may be set as far in advance of the operation of the escapement mechanism as may be necessary in order to secure the proper tension on the spring 96, while the offset terminal of the band 90 will maintain the same starting position with respect to the collar 92 owing to the fact that the band will engage the insulating block 95 and be held against further rotation with the hub 85 of the gear 81.

My two electric circuits have been enumerated above, and the succeeding parts of each channel enunciated in detail and it is clear from the description that the two circuits no where overlap or lead into each other. Nevertheless the second circuit is automatically operated from the first. The means for accomplishing this result are as follows:

The first circuit, namely the one leading from the synchronizer through the solenoids 78 to the escapement is adapted when closed to release the escapement for its initial rotation in advance of the phonograph. This causes the collar 92, which is rigidly connected to the escapement shaft 62, to rotate therewith into contacting engagement with the inwardly offset end of band 90 as shown in Fig. 6, since the latter is connected for movement with gear 81 and the phonograph, not yet released for movement. But the relative movement of the band 90 and the collar 92 into and out of engagement with each other, constitutes the closing and opening of the second circuit switch, namely of the one having its current flowing through solenoids 98. These solenoids are accordingly energized by the closing of said switch 90-92 and serve by the means of shoe brakes 103 to start the phonograph at maximum speed, to enable it to keep up

with the escapement and synchronizer and the projection machine.

It will now be clear that, briefly stated, my synchronizing mechanism comprises a synchronized circuit from the projection machine, an escapement released by said synchronized circuit and operated by motive power derived from the phonograph motor to close a second circuit switch and energize electric clutch means to start the phonograph at maximum speed and to maintain it in synchronism with the picture projecting machine or a plurality of phonographs with each other. It is further obvious, as already stated, that the moving picture projecting machine may be dispensed with and the synchronizing apparatus driven by any other means. The shaft shown in Fig. 1, having the sprocket gear 32 and the sprocket chain 31 to the synchronizing apparatus, may be driven by any other means than a picture projection machine. Finally it is obvious that the phonograph may also be discarded as a sound reproducing machine and the record disc R become a mere part of an electrical switching device to perform the functions above described, for any purpose.

In practice, after the film has been developed and the records made, a distinguishing mark is made on the film at a few feet from the beginning of the film to indicate the starting point. The tape 42 in the synchronizing mechanism has a corresponding indicative mark thereon. In the event that a break should occur in the picture film and say four pictures are taken out, a length of the tape 42 equivalent to the distance between four of the perforations in the tape, is removed so that perfect synchronism will be established when the sound reproducing machine is again operated. It is of course also understood that the reproducing needle or stylus is offset at a point in the record groove corresponding to the starting point on the tape 42.

When it is necessary to adjust the tape or web 42 for the proper positioning of the rows of perforations with respect to the circuit closer 36 and in relation to the picture film in starting, the pin 29 is pulled outwardly so that the gear 25 is shifted axially through the medium of the resilient arm 28 out of meshing engagement with the gear 35. The tape may then be withdrawn from the reel 9 and wound upon the reel 10 without rotating the shaft 34 carrying the circuit closing rings 36.

In Figure 11 of the drawings I have shown a slightly modified means for closing the circuit controlling the operation of the escapement mechanism, wherein the shaft 34 and the rings 36 carrying the pins 39 are dispensed with, and the spring contact

members 47 have their free ends or terminals 65 formed for engagement through the rows of perforations in the tape 42 and directly upon the current conducting sleeve 18. While this arrangement is somewhat simpler than that hereinbefore referred to, the 70 provision of the spring pressed pins 39 insures a more effective contact with the circuit closing sleeve and for a relatively long period of time so that there will be no breakage in the continuity of the current. 75

From the foregoing description taken in connection with the accompanying drawing, the construction, manner of operation and several advantages of my improved synchronizing mechanism will be clearly and fully 80 understood. While the invention is adapted for use in the synchronization of the operation of sound reproducing machines and picture projecting apparatus, it will at once be manifest that the mechanism may 85 also be advantageously employed for operation in various other machines, such for instance, as those used in display advertising, electrical signs and stereopticon lectures, as well as in synchronizing sound re- 90 producing or musical machines with each other, independently of any picture projecting apparatus. The mechanism as a whole is comparatively simple in its construction as well as positive and reliable in operation. 95 While I have herein shown and described the present preferred construction and arrangement of the several parts, it is to be understood that the mechanism is susceptible of many modifications therein and I 100 therefore reserve the privilege of adopting all such legitimate changes as may be fairly embodied within the spirit and scope of the invention as claimed.

Having thus fully described my invention, what I claim and desire to secure by Letters Patent is:—

1. The combination with two machines adapted to be operated in synchronized relation, of mechanism having an electric circuit 110 and operable to start the operation of one of said machines, means having a second electric circuit automatically closed upon the closing of the first said circuit to effect said initial operation at maximum effective 115 speed, and means operatively controlled by the other of said machines to effect the operation of said mechanism and said means at predetermined times.

2. The combination with two machines 120 adapted to be operated in synchronized relation, of electrically controlled mechanism having a circuit and operable to start the operation of one of said machines, electrically controlled means having a second 125 circuit automatically closed upon the closing of the first said circuit to effect said initial operation at maximum effective

speed, and means cooperatively associated with the other of said machines to close said circuits at predetermined times in the operation of the latter machine.

5 3. The combination with two machines adapted to be operated in synchronized relation, of mechanism operable to start the operation of one of said machines, a circuit controlling said mechanism, said circuit being under control of the other of said machines, a second circuit, means operating when the second circuit is closed to effect the operation of the said one machine at maximum effective speed and when the second circuit is opened, to abruptly stop the said one machine, and means automatically operating, when the said mechanism is started, to close said second circuit and when said mechanism is stopped to open said second circuit.

20 4. The combination with two machines adapted to be operated in synchronizing relation, of mechanism operable to start the operation of one of said machines, a circuit controlling said mechanism, means cooperatively associated with the other of said machines to close and open said circuit at predetermined times, a second circuit, means operating, when the second circuit is closed, to effect the operation of the said one machine at maximum effective speed, and when the said second circuit is opened, to abruptly stop the said one machine, and means controlling the second circuit, and rendered operable by the operation of the said one machine to open the second circuit after the first circuit is opened.

25 5. The combination with two machines to be operated in synchronized relation, of electrically controlled mechanism operable to start the operation of one of said machines at maximum effective speed, a circuit therefor, means cooperatively associated with the other of said machines to close the circuit at predetermined times, and means rendered operable by the operation of the first named machine after the circuit for said mechanism is broken, to stop the continued operation of the first named machine, said mechanism including a part rendered effective by the subsequent operation of said first named machine to start the operation of said mechanism at maximum speed when the circuit therefor is closed.

30 6. The combination with two machines to be operated in synchronized relation, of mechanism controlling the operation of one of said machines, means operatively associated with the other machine to effect the operation of said mechanism at predetermined times, means to prevent the operation of the first named machine when said mechanism is inactive and means automatically operated upon the initial ac-

45 tuation of said mechanism to effect the operation of said last named means and thereby permit the operation of the first named machine.

7. The combination with two machines to be operated in synchronized relation, of mechanism controlling the operation of one of said machines, means cooperatively associated with the other machine to effect the operation of said mechanism at predetermined times, means to prevent the operation of said first named machine when said mechanism is inactive, electrical means to render the last named means inoperative and a circuit therefor, and means for closing said circuit operated upon the initial 75 actuation of said mechanism to thereby permit of the operation of the first named machine.

8. The combination with two machines to be operated in synchronized relation, of mechanism controlling the operation of one of said machines, electrical means to effect the operation of said mechanism having a circuit, means cooperatively associated with the other machine to close said circuit at 80 predetermined times, means to prevent the operation of the first named machine when said mechanism is inactive, and means automatically operated upon the initial actuation of said mechanism to effect the operation of said last named means and permit the first named machine to operate.

9. The combination with two machines to be operated in synchronized relation, of mechanism controlling the operation of one of said machines, electrical means to effect the operation of said mechanism having a circuit, means cooperatively associated with the other machine to close said circuit at predetermined times, means to prevent the operation of the first named machine when said mechanism is inactive, electrical means operable to render said last named means inoperative, and means operated in the initial actuation of said mechanism to close 100 the circuit, for said electrical means and thereby permit the first named machine to operate.

10. The combination with two machines to be operated in synchronized relation, of mechanism automatically controlled by one of said machines to effect the operation of the other machine at predetermined times during the operation of the first named machine, said mechanism including means rendered operable by the second named machine in its operation to effect the operation of the second named machine at maximum effective speed in the initial actuation of said mechanism.

11. The combination with two machines to be operated in synchronized relation, of electrically controlled mechanism coopera-

- tively associated with one of said machines to effect the operation of the other machine at predetermined times in the operation of the first named machine, said mechanism including means rendered operable by the second named machine in its operation to effect the operation of the second named machine at maximum effective speed in the initial actuation of said mechanism.
- 10 12. The combination with two machines to be operated in synchronized relation, of electrically controlled mechanism cooperatively associated with one of said machines to effect the operation of the other machine at predetermined times in the operation of the first named machine, said mechanism including a movable perforated tape and circuit closing means operable through the perforations in the tape, said mechanism further including means rendered operable by the second named machine in its operation to effect the operation of the second named machine at maximum effective speed in the initial actuation of said mechanism.
- 15 13. The combination with two machines to be operated in synchronized relation, of mechanism automatically controlled by one of said machines to effect the operation of the other machine at predetermined times during the operation of the first named machine, said mechanism including means rendered operable by the second named machine in its operation to effect the operation of the second named machine at maximum effective speed in the initial actuation of said mechanism, mechanically applied brake means for the second named machine, and electrical means rendered operable in the initial actuation of said mechanism to effect the release of said brakes and permit the operation of said machine.
- 20 14. The combination with two machines to be operated in synchronized relation, of power propelling means and an escapement mechanism controlling the operation of one of said machines, means cooperatively associated with the other machine to effect the operation of said mechanism at predetermined times, and means constituting the operative connection between the operating means for said first named machine and said mechanism, constructed to effect the initial actuation of the escapement mechanism at maximum speed.
- 25 15. The combination with two machines to be operated in synchronized relation, of power propelling means and an escapement mechanism controlling the operation of one of said machines, means cooperatively associated with the other machine to effect the operation of said mechanism at maximum speed, and means rendered operable prior to the effective operation of said stop means, and means rendered operable during such operation of said machine to effect the initial operation of said escapement mechanism at maximum speed.
- 30 16. The combination with two machines to be operated in synchronized relation, of power propelling means and an escapement mechanism controlling the operation of one of said machines, means cooperatively associated with the other machine to effect the operation of said mechanism at predetermined times, automatically operable stop means for the first named machine, said machine operating for a limited time after the escapement mechanism becomes inactive and prior to the effective operation of said stop means, and means constituting the operating connection between the operating means for said machine and the escapement mechanism rendered operable during such limited operation of the first named machine to effect the initial actuation of said escapement mechanism at maximum speed.
- 35 17. The combination with two machines to be operated in synchronized relation, of power propelling means and an escapement mechanism controlling the operation of one of said machines, electrical means cooperatively associated with the other machine to automatically effect the operation of said mechanism at predetermined times, and a tensionable element constituting the operating connection between the operating means of said first named machine and said escapement mechanism adapted to effect the initial actuation of the escapement mechanism at maximum speed.
- 40 18. The combination with two machines to be operated in synchronized relation, of power propelling means and an escapement mechanism controlling the operation of one of said machines, means cooperatively associated with the other machine to effect the operation of said mechanism at predetermined times, normally effective stop means preventing the operation of the first named machine, electrically controlled means to render the stop means ineffective and permit the operation of said machine, a circuit therefore, and a circuit closer automatically actuated in the initial actuation of the escapement mechanism.
- 45 19. The combination with two machines to be operated in synchronized relation, of power propelling means and an escapement mechanism controlling the operation of one of said machines, means cooperatively associated with the other machine to effect the operation of said mechanism at predetermined times, normally effective stop means preventing the operation of the first named machine, electrically controlled means to render the stop means ineffective and permit the operation of said machine, a circuit

- therefor, and a circuit closer automatically operable in the initial actuation of the escapement mechanism, said circuit closer including a conductor carried by one of the 5 elements of the operating mechanism for said first named machine and a contact member to engage said conductor carried by one of the elements of the escapement mechanism.
- 10 20. The combination with two machines to be operated in synchronized relation, of power propelling means and an escapement mechanism controlling the operation of one of said machines, means cooperatively associated with the other machine to effect the operation of said mechanism at pre-determined times, normally effective stop means preventing the operation of the first named machine, electrically controlled 15 means to render the stop means ineffective and permit the operation of said machine, a circuit therefor, and a circuit closer automatically operable in the initial actuation of the escapement mechanism, said circuit closer including a conductor carried by one of the elements of the operating mechanism for said first named machine, a contact member to engage said conductor carried by one of the elements of the escapement mechanism, said machine operating for a limited 20 time after the escapement mechanism becomes inactive whereby the conductor is disengaged from said contact to break the circuit and permit the stop means to return 25 to its effective position, and means rendered operable during such operation of the machine to effect the initial actuation of the escapement mechanism at maximum speed upon the subsequent operation of said mechanism.
- 30 40 21. The combination with two machines to be operated in synchronized relation, of power propelling means and an escapement mechanism controlling the operation of one of said machines, means cooperatively associated with the other machine to effect the operation of said mechanism at predetermined times, normally effective stop means preventing the operation of the first named machine, electrically controlled means to render the stop means ineffective and permit the operation of said machine, a circuit therefor, and a circuit closer automatically operable in the initial actuation of the escapement mechanism, said circuit closer including a conductor carried by one of the elements of the operating mechanism for said first named machine, a contact member to engage said conductor carried by one of the elements of the escapement mechanism, said machine operating for a limited time after the escapement mechanism becomes inactive whereby the conductor is disengaged from said contact to break the circuit and permit the stop means to return to its effective position, and a tensionable element connecting parts of the operating means for said machine and of the escapement mechanism and rendered operable by such limited continued operation of the machine to effect the initial actuation of the escapement mechanism at maximum speed upon the subsequent operation thereof.

22. The combination with two machines to be operated in synchronized relation, of power propelling means and an escapement mechanism controlling the operation of one of said machines, means cooperatively associated with the other machine to effect the operation of said mechanism at predetermined times, normally effective stop means preventing the operation of the first named machine, electrically controlled means to render the stop means ineffective and permit the operation of said machine, a circuit therefor, and a circuit closer automatically operable in the initial actuation of the escapement mechanism, said circuit closer including a movable conductor carried by one of the elements operatively connecting the escapement mechanism with said machine, and a contact member carried by a part of the escapement mechanism to coact with said conductor, said machine operating for a limited time after the escapement mechanism becomes inactive whereby said conductor is moved by said element out of engagement with the contact to break the circuit of the stop means and permit of the effective operation thereof.
23. In combination, a sound reproducing instrument, propelling power therefor, an escapement to control said instrument against the propelling power and means for actuating the escapement, said means including a synchronizer and an electric circuit from the synchronizer to the escapement and a perforated tape at the synchronizer for selectively making and breaking the current in said circuit.
24. In combination, a plurality of sound reproducing instruments, propelling power therefor, an escapement to control each sound reproducing instrument against its propelling power and means for actuating the several escapements in synchronism with each other, said means including a synchronizer and an electric circuit from the synchronizer to each escapement and a perforated tape at the synchronizer for selectively making and breaking the current in the several circuits.
25. The combination with a moving picture projecting apparatus, and a plurality of sound reproducing machines, of electrically controlled escapement mechanisms associated each with one of the sound reproducing machines and controlling the operation thereof, a circuit for each escapement mechanism, and circuit control means co-

operatively associated with the picture projecting apparatus, and including means whereby while the picture projecting apparatus is continuously operating the circuits of the several escapement mechanisms may be made and broken independently of each other and at varying intervals.

26. The combination with a moving picture projecting apparatus and a plurality of sound reproducing machines to be operated in synchronized relation with said apparatus, of an electrically operated escapement mechanism for each sound reproducing machine controlling the operation thereof, and means cooperatively associated with the picture projecting apparatus to make and break the circuits of the several escapement mechanisms at predetermined times and synchronously operate the sound reproducing machines independently of each other, said means including a perforated tape operable in timed relation with the picture projecting apparatus and circuit closing contacts engageable through the perforations in the tape to close the respective circuits.

27. The combination with a moving picture projecting apparatus and a plurality of sound reproducing machines to be operated in synchronized relation with said apparatus, of an electrically operated escapement mechanism for each sound reproducing machine controlling the operation thereof, and means cooperatively associated with the picture projecting apparatus to make and break the circuits of the several escapement mechanisms at predetermined times and synchronously operate the sound reproducing machines independently of each other, said means including a tape operable in timed relation with the picture projecting apparatus and provided with spaced rows of perforations corresponding to the number of sound reproducing machines, and a series of yieldable contact members engageable through the respective series of perforations in the tape to close the circuits for the several escapement mechanisms.

28. The combination with a moving picture projecting apparatus and a sound reproducing machine, of an escapement mechanism controlling the operation of the sound reproducing machine, and control means for the escapement mechanism cooperatively associated with the moving picture projecting apparatus, and including means whereby while the picture projecting apparatus is continuously operating, the operation of the escapement mechanism may be effected at various times and for various periods.

29. The combination with a moving picture projecting apparatus and a sound reproducing machine, of means for synchronizing the operation of said machines including an escapement mechanism controlling

the operation of the sound reproducing machine, means operatively associated with the moving picture projecting apparatus to effect the operation of the escapement mechanism at predetermined times, and additional means automatically operable to effect the initial actuation of the escapement mechanism at maximum speed.

30. The combination with a moving picture projecting apparatus and a sound reproducing machine, of means for synchronizing the operation of said machines including an escapement mechanism controlling the operation of the sound reproducing machine, normally effective brake means for the sound reproducing machine, and means associated with the moving picture projecting apparatus for effecting the release of the brake means and the actuation of the escapement mechanism.

31. The combination with a moving picture projecting apparatus and a sound reproducing machine, of means for synchronizing the operation of said machines including an escapement mechanism controlling the operation of the sound reproducing machine, normally effective brake means for the sound reproducing machine, means associated with the moving picture projecting apparatus for effecting the release of the brake means and the actuation of the escapement mechanism, and means constituting part of the operating connection between the escapement mechanism and the sound reproducing machine for effecting the initial actuation of the escapement mechanism at maximum speed.

32. The combination with a moving picture projecting apparatus and a sound reproducing machine, of means for synchronizing the operation of said machines including propelling power and an escapement mechanism controlling the operation of the sound reproducing machine, brake means normally effective to prevent the operation of the sound reproducing machine, means operatively associated with the moving picture projecting apparatus to effect the release of the brake means, and additional means operable subsequently to said release to actuate the escapement mechanism at maximum speed.

33. The combination with a moving picture projecting apparatus and a sound reproducing machine, of means for synchronizing the operation of said machines including an escapement mechanism controlling the operation of the sound reproducing machine, a normally effective brake for said machine, means operatively associated with the picture projecting apparatus to release the brake at predetermined times, means automatically operable to effect the actuation of the escapement mechanism, and means constituting the operative connection

between the escapement mechanism and the sound reproducing machine and operable independently of the mechanism prior to the application of the brake to effect the subsequent initial actuation of the escapement mechanism at maximum speed.

34. The combination with a moving picture projecting apparatus, and a plurality of sound reproducing machines, of starting and stopping mechanism of each machine operable independently of each other, to initially start each machine at maximum speed and abruptly stop each machine, means associated with each starting and stopping mechanism for automatically operating its associated starting and stopping mechanism to start its sound reproducing machine at maximum speed and abruptly stop it, and synchronizing mechanism connected to and automatically operable by a moving picture projecting machine and having means for independently controlling each of the first said means.

35. The combination with a moving picture projecting apparatus and a plurality of sound reproducing machines to be operated in synchronous relation with said apparatus, of an escapement mechanism for each sound reproducing machine controlling the operation thereof, and means common to all of the escapement mechanisms associated with the picture projecting apparatus to effect the actuation of the escapement mechanisms at predetermined times and synchronously operate the sound reproducing machines independently of each other.

36. The combination, with a picture projecting machine and a sound reproducing machine, of an escapement to control the sound reproducing machine, a synchronizing mechanism operable from the picture projection machine, an electric circuit from the synchronizing mechanism to the escapement and means in the said mechanism to selectively make and break the current in said circuit to selectively control the operation of the escapement.

37. In combination with a sound reproducing machine, an escapement mechanism operatively geared to said machine and controlling the operation thereof, and means associated with the connecting gearing and rendered effective by the operation thereof to initially actuate the escapement mechanism at maximum speed.

38. In combination with a sound reproducing machine, an escapement mechanism operatively geared to said machine and controlling the operation thereof, a normally effective brake for said machine and means for automatically releasing said brake at predetermined times, and means associated with the gearing connecting the escapement mechanism to said machine and rendered effective by the operation of said gearing to

initially actuate the escapement mechanism at maximum speed.

39. In combination with a sound reproducing machine, an escapement mechanism operatively geared to said machine and controlling the operation thereof, a normally effective brake preventing the operation of said machine, means to release said brake at predetermined times, means for automatically interrupting the operation of the escapement mechanism prior to the application of the brake, and means automatically rendered effective prior to the application of the brake to initially actuate the escapement mechanism at maximum speed in the subsequent operation thereof.

40. In combination with a sound reproducing machine, an escapement mechanism operatively geared to the operating means for said machine, means for automatically controlling the operation of the escapement mechanism, a normally effective brake for said machine, electrically controlled releasing means for said brake, and a circuit therefor, and circuit closing means automatically operated in the initial actuation of the escapement mechanism to close said circuit and release the brake.

41. In combination with a sound reproducing machine, an escapement mechanism operatively geared to the operating means for said machine, means for automatically controlling the operation of the escapement mechanism, a normally effective brake for said machine, means for releasing the brake, and means automatically operated in the initial actuation of the escapement mechanism to render said brake releasing means operative and permit of the operation of the machine.

42. The combination with two machines to be operated in synchronized relation, of mechanism controlling the operation of one of said machines, means co-operatively associated with the other machine to automatically effect the operation of said mechanism at predetermined times, and means rendered effective by the operation of the first named machine to initially actuate said mechanism at maximum speed.

43. The combination with two machines to be operated in synchronized relation, of electrically controlled mechanism co-operatively associated with one of said machines to operate the other machine at predetermined times, and means rendered effective by the operation of the latter machine to initially actuate said mechanism at maximum speed.

44. The combination with two machines adapted to be operated in synchronized relation, of mechanism cooperatively associated with one of said machines and automatically controlled thereby to effect the initial actuation of the other machine, means whereby

the initial actuation of the said other machine may be made at maximum speed, and means for automatically effecting the actuation of last said means when said mechanism is operated, to effect the initial actuation of said other machine.

45. The combination with a plurality of independently power driven machines, of means associated with each machine for initially starting each machine at maximum speed and for abruptly stopping said machine, a synchronizing mechanism, and a plurality of means controlled individually and independently of each other by the synchronizing mechanism and each including means for automatically controlling the action of its associated starting and stopping means.

46. The combination with a sound reproducing machine, of an escapement mechanism controlling the operation of said machine, and means rendered effective by the operation of said machine to initially actuate the escapement mechanism at maximum speed.

47. The combination with a sound reproducing machine, of an escapement mechanism controlling the operation of said machine, a normally effective brake for the sound reproducing machine, means for automatically releasing said brake at predetermined times, and means rendered effective by the operation of said machine to initially actuate the escapement mechanism at maximum speed.

48. The combination with a plurality of independently power driven machines of a synchronizing mechanism for controlling the machines, and mechanisms associated with each power driven machine and interposed between the synchronizing mechanism and such machine, and subject to control by the synchronizing mechanism and including means for automatically initially starting each power driven machine at maximum speed and abruptly stopping each power driven machine.

49. In combination, a musical instrument, propelling power therefor, an escapement to control said instrument against the propelling power, means for actuating the escapement to permit operation of the musical instrument under the influence of the propelling power, and a clutch mechanism electrically actuated by the escapement actuating means for starting the musical instrument at maximum speed upon the initial operation of the escapement and mechanically actuated for bringing the said instrument from full maximum speed to stark stand still instantly the actuation of the escapement ceases.

50. In combination, a sound reproducing machine, propelling power therefor, an escapement to control said machine against the propelling power, means for actuating the

escapement to permit operation of said machine under the influence of the propelling power, and a clutch mechanism electrically actuated by the escapement actuating means for starting the sound reproducing instrument at maximum speed upon the initial operation of the escapement and mechanically actuated for bringing the said instrument from full maximum speed to stark stand still instantly the actuation of the escapement ceases.

51. The combination with a plurality of independently power driven machines of mechanisms associated with each machine for initially starting it at maximum speed and for abruptly stopping it, and a continuously operating synchronizing mechanism, including means for independently controlling each said starting and stopping means.

52. The combination, with a moving picture projecting apparatus and a phonograph adapted to be operated in synchronized relation, of a synchronizing mechanism co-operatively associated with the picture projecting apparatus, an escapement co-operatively associated with the phonograph, an electric circuit from the synchronizing mechanism to the escapement and a switch therefor in the synchronizing mechanism timed to open and close the circuit synchronously with the projection of the moving pictures, to effect the step by step operation of the escapement in synchronism therewith, and a flexible connection between the escapement and the sound reproducing machine, to permit of the transposition of the synchronized step by step movement of the escapement into a continuous movement of the sound reproducing machine in synchronism with the projection of the moving pictures.

53. In combination, a power driven sound-reproducing instrument, propelling power therefor, an escapement to control said instrument against the propelling power, and means for actuating the escapement, said means including an electric circuit and a perforated web for selectively controlling the operation of the several escapements.

54. In combination, a plurality of power driven sound-reproducing instruments, propelling power therefor, an escapement to control each sound-reproducing instrument against its propelling power, and means for actuating the several escapements in synchronism with each other, said means including a plurality of electric circuits and a perforated web for selectively controlling the operation of the several escapements.

55. The combination with a synchronizing apparatus and a plurality of sound reproducing machines adapted to be operated in synchronism with each other, of an escapement mechanism co-operatively associated with each sound reproducing machine, an electric circuit between the synchronizing

mechanism and each escapement and a switch in each circuit in the synchronizing apparatus, to effect the step by step operation of the several escapements in synchronism with each other, and a flexible connection between each escapement and its sound reproducing machine, to permit of the transposition of the synchronized step by step movement of the several escapements into a continuous movement of the several sound reproducing machines in synchronism with each other.

56. The combination, with a picture projecting machine and a sound-reproducing machine, of an escapement to control the sound-reproducing machine, an electric circuit to control the escapement, and a perforated web operable from the picture projection machine to make and break said circuit to selectively control the operation of said escapement.

57. The combination, with a moving picture projecting apparatus and a sound reproducing machine to be operated in synchronized relation, of a synchronizing mechanism co-operatively associated with the picture projecting apparatus, an escapement and a solenoid and an operative means co-operatively associated with the sound reproducing machine, an electric circuit from the synchronizing mechanism to the escapement and a second electric circuit from the escapement to the solenoid, a switch in the synchronizing mechanism to make and break the circuit to the escapement to effect a step by step movement of the latter synchronously with the projection of the pictures, a switch in the escapement to make and break the circuit to the solenoid and means in the

escapement to automatically maintain the circuit to the solenoid closed during said step by step movement, to effect the continuous energizing of the solenoid and its continuous operation on the said means during the said step by step movement of the escapement.

58. The combination with a synchronizing apparatus and a plurality of sound reproducing machines to be operated in synchronism with each other, of an escapement and a solenoid and an operative means co-operatively associated with each sound reproducing machine, an electric circuit from the synchronizing apparatus to each said escapement and a second electric circuit from the several escapements to their associated solenoids, switches in the synchronizing apparatus to independently make and break the circuits to the several escapements to selectively effect the step by step movement of each escapement synchronously with the projection of the pictures, a switch in each escapement to make and break the circuit to each said solenoid and means in the several escapements to automatically maintain the switches closed during said step by step movement, whereby to effect the continuous energizing of the respective solenoids and their continuous operation on the said means during the step by step movement of the respective escapements.

In testimony whereof I hereunto affix my signature in the presence of two witnesses.

THOMAS L. DENNIS, JR.
